UNITED STATES PATENT OFFICE.

DANIEL SCHMEIDLER, OF ATLANTIC CITY, NEW JERSEY.

DESIGN FOR A FLOOR LAMP-BASE.

57,383.

Specification for Design.

Patented Mar. 15, 1921.

Application filed September 8, 1920. Serial No. 409,007. Term of patent 3½ years.

To all whom it may concern:

Be it known that I, DANIEL SCHMEIDLER, a citizen of the United States, residing in Atlantic City, in the county of Atlantic and State of New Jersey, have invented a new, original, and ornamental Design for a Floor Lamp-Base, of which the following is a specification, reference being had to the accompanying drawing, forming a part hereof.

The figure is a perspective view of my novel design.

I claim:—

The ornamental design for a floor lamp base, substantially as shown.

This specification signed this 3rd day of Sept., 1920.

DANIEL SCHMEIDLER.
